(57) **CLAIM**

The ornamental design for a deadbolt throw latch, as shown and described.

DESCRIPTION

FIG. 1 is a perspective view of a first embodiment of a deadbolt throw latch in accordance with the present invention;

FIG. 2 is a front elevational view thereof;

FIG. 3 is a top view thereof;

FIG. 4 is a left side view thereof;

FIG. 5 is a right side view thereof;

FIG. 6 is perspective view of a second embodiment of a deadbolt throw latch of the invention; and,

FIG. 7 is a front elevational view thereof.
